TUBING ANCHOR

Charles C. Douglass, Tioga, N. Dak., and Robert T. Evans, Duncan, Okla., assignors to Halliburton Company, a corporation of Delaware

Filed Apr. 7, 1960, Ser. No. 20,589
3 Claims. (Cl. 166—216)

This invention relates to tubing anchors for use in oil wells, and more particularly to an arrangement for holding and removing tubing in a well if, by accident, it has parted at some point above its lower end.

It is common practice to use steel tubing in oil wells. Sometimes, due to excessive strain, or due to corrosion, or other factors, the tubing comes apart at some point in the well. The lower portion of the tubing then falls and is damaged, and an expensive fishing job is then necessary to remove it.

For preventing the falling of parted tubing, "catchers," per se, are old in the art. However, ordinary catchers are not suitable for use with slips or other latch-down devices which hold the lower end of the tubing against upward movement during normal operation.

It is an object of the present invention to provide an anchor for tubing used in a well which is capable of latching or fastening down its lower end, and at the same time prevent the tubing from falling, in case it parts. An arrangement is provided for rendering the latch-down mechanism inactive, should a fishing job be required, so that the parted tubing can readily be retrieved.

Other objects will be apparent from the following description of a preferred embodiment of the invention, when taken in connection with the accompanying drawings, in which:

FIGURE 1 is a view in vertical cross section of a portion of an oil well with a tubing anchor constructed in accordance with the invention located therein, the parts being shown in the relative positions they occupy while tubing is being lowered into the well;

FIGURE 2 is a vertical quarter section of the anchor of FIGURE 1, showing the parts in the relative positions they occupy when the latch-down mechanism is in use during normal operation of the tubing in the well;

FIGURE 3 is a vertical quarter section of the anchor of FIGURE 1, showing the parts in the relative positions they occupy when the tubing comes apart at some point above the anchor;

FIGURE 4 is a vertical quarter section of the anchor of FIGURE 1 showing the parts in the relative positions which they occupy when a fishing operation is being conducted to remove the parted tubing from the well; and

FIGURE 5 is an elevational view of the J-slot shown in section in FIGURES 1-4.

Referring to the drawing in detail, it will be seen that FIGURE 1 shows a casing 10 cemented in a well bore. On the lower end of tubing 11, there is an anchor consisting essentially of a mandrel 12, which is connected to the lower end of the tubing 11 by a threaded coupling 13, and an outer sleeve 14 threaded upon the mandrel 12 by right-hand acme threads 15.

At its lower end, the mandrel 12 is provided with a tapered conical wedge or spreader block 16; and at the lower end of the sleeve 14, there is a cooperating tapered conical wedge or spreader block 17.

Coacting with the spreader blocks are conventional slips 18 which have tapered inner surfaces corresponding to those of the spreader blocks.

It will be seen that the spreader blocks 16 and 17 are so disposed as to face each other, so that either block can force the coacting slips 18 outwardly, the block 16 acting on the slips 18 when the tubing 11 is raised in the

2

casing 10 and the block 17 acting on the slips 18 when the tubing 11 is lowered in the casing 10.

It will be observed that the lower end of the sleeve 14 abuts against a shoulder 19 on the mandrel 12. Thus the blocks on sleeve 14 and mandrel 12 cannot be brought any closer together than shown in FIGURE 1. However by rotation of mandrel 12 to the right (as viewed from above) the spreader blocks 16 and 17 may be separated further, if the sleeve 14 is held against rotation.

The slips 18 are held in position between the spreader blocks 16 and 17 by a suitable cage 20 and drag springs 21.

The cage 20 consists merely of an outer cylinder provided with windows in which the slips 18 are yieldably held by leaf springs 22.

The cage 20 is provided with conventional pins 23 extending into conventional J-slots 24 on the sleeve 14, so that there can be only limited relative longitudinal movement between the cage 20 and the sleeve 14 when the parts are in the running-in position shown in FIGURE 1. As shown in FIGURES 1 and 5, each J-slot 24 includes a first generally elongate slot portion 24a extending axially of the anchor, a second elongate portion 24b also extending axially of the anchor, and a transversely extending portion 24c connecting the intermediate part of portion 24b with portion 24a of the slot. In the running-in position, pins 23 are positioned in slot portions 24a which are of limited axial extent so as to restrict axial movement of the cage 20 to thereby prevent coaction between the spreader blocks and slips.

As long as the J-slot coupling is limiting relative longitudinal movement between the cage 20 and the sleeve 14, neither of the spreader blocks can force the slips 18 outwardly. When the tubing has been lowered to the desired point in the well at which it is desired that the lower end be anchored, the tubing is rotated to the left sufficiently to bring the pins 23 into the longer portions 24b of the J-slots 24. This is possible because of the shoulder 19 on the mandrel 12. The sleeve 14 cannot move downwardly on the mandrel 12 upon left-hand rotation of the mandrel due to this shoulder. Hence the left hand torque on the mandrel 12 is transmitted to the sleeve 14 to operate the J-slot connector.

There is then a situation where either of the blocks can set the slips 18 in the casing 10, the slips being held against falling by the drag springs 21 and the cage 20 while the tubing 11, mandrel 12 and sleeve 14 can be moved up or down with respect to the slips 18.

To place the parts of the anchor in the operating position shown in FIGURE 2, all that is necessary, therefore, is to turn the tubing slightly to the left and raise it.

When the spreader block 16 causes the slips 18 to grasp the casing, tension can be taken in the tubing. This is desired, for example, when the tubing is provided with a pump, and it is desired to avoid "breathing" or buckling of the tubing with each pump stroke.

Should the tubing come part, as illustrated in FIGURE 3, the slips 18 are held against downward movement by the drag springs 21 and cage 20 until the tubing falls far enough for the spreader block 17 to cause them to again grip the casing.

To remove the parted tubing from the well, a fishing device, such as is illustrated at 25 is connected to the parted tubing. An attempt would then be made to rotate the tubing to the right and cause the pins 23 to re-enter the horizontal portions of the J-slot 24. If this can be brought about, the parted tubing can be fished out.

However, it may not be possible to effect the proper actions of the pins 23 and J-slots 24. In that event, continued right-hand rotation of the tubing will cause the spreader blocks 16 and 17 to separate to such a distance that the anchor can still be moved upwardly in the well.

This is brought about by the action of the acme thread 15 between the sleeve 14 and the mandrel 12.

During the right-hand rotation, the cage 20 will be held against rotation either by the slips 18 or by the drag springs 21. The cage 20, through the pins 23 and slots 24, will hold the sleeve 14 against rotation. The mandrel 12 is free to rotate in the sleeve 14 in a right-hand direction however, and since it is connected to the tubing 11, this action can be brought about. The result is that the parted tubing and the anchor can be removed from the well regardless of the fact that the J-slot connector cannot be manipulated.

While only one embodiment of the invention has been shown and described, it is obvious that various changes may be made without departing from the spirit of the invention, or the scope of the annexed claims.

What is claimed is:

1. An anchor for tubing in an oil well or the like comprising a mandrel and sleeve assembly including a mandrel adapted to be connected to the tubing and a sleeve screw-threaded on the mandrel and upwardly movable thereon; an upwardly directed spreader block carried by said mandrel; a downwardly directed spreader block carried by said sleeve above said upwardly directed spreader block; slips for engaging casing in the well positioned between said spreader blocks and having upper surface means adapted to coact with said sleeve carried spreader block and lower surface means adapted to coact with said mandrel carried spreader blocks, a cage encircling said mandrel and sleeve assembly for holding said slips, said cage being slidably mounted on said assembly; drag springs projecting from the exterior of said cage to engage a well wall; a J-slot on the exterior of said sleeve, said J-slot having a first slot portion extending axially of said anchor, a second elongate portion extending axially of said anchor, and a transversely extending portion connecting an intermediate part of said second portion and said first portion; and a pin extending from said cage into said J-slot, said pin, when in said first slot portion limiting axial cage movement to prevent said coaction between said spreader blocks and said slips, and when moved through said transversely extending slot portion into said second elongate slot portion, permitting said coaction.

2. An anchor as defined in claim 1 in which said sleeve is mounted on said mandrel by a right hand threaded connection and in which said mandrel is provided with a shoulder beneath the lower end of said

5 sleeve such that, with said sleeve engaging said shoulder, and said pin in said first axially extending slot portion and opposite said transversely extending slot portion, a left hand torque applied to said mandrel to move said pin through said transversely extending slot portion into said second elongate slot portion will not effect movement of said sleeve on said mandrel.

3. An anchor for tubing in an oil well or the like comprising a mandrel and sleeve means assembly including a mandrel adapted to be connected to the tubing and sleeve means mounted on the mandrel and upwardly movable thereon; an upwardly directed spreader block carried by said mandrel; a downwardly directed spreader block carried by said sleeve means above said upwardly directed spreader block; slips for engaging casing in the well positioned between said spreader blocks and having upper surface means adapted to coact with said sleeve means carried spreader block and lower surface means adapted to coact with said mandrel carried spreader blocks, cage means encircling said mandrel and sleeve means assembly for holding said slips, said cage means being slidably mounted on said assembly; drag springs projecting from the exterior of said sleeve means to engage a well wall; a J-slot connection between said cage means and said sleeve means, said connection including a J-slot on one of said means, said J-slot having a first slot portion extending axially of said anchor, a second elongate portion extending axially of said anchor, and a transversely extending portion connecting an intermediate part of said second portion and said first portion; and a pin extending from the other of said means into said J-slot, said pin, when in said first slot portion limiting axial cage means movement to prevent said coaction between said spreader blocks and said slips, and when moved through said transversely extending slot portion into said second elongate slot portion, permitting said coaction.
